SHOE

Benjamin Benjamin, Freeport, N. Y., assignor to
Schwartz & Benjamin, Incorporated, Brooklyn,
N. Y.

Application April 6, 1936, Serial No. 73,010

8 Claims. (Cl. 36—58.5)

This invention relates to footwear of the type in which it is desirable to use saddle straps or stays. By footwear is meant shoes, slippers, pumps, sandals, oxfords, etc., of various designs and structure. More specifically the invention relates to a novel strap or stay in combination with a conventional type of shoe.

The most important field of utility in which the invention is to be employed is found in women's shoes. The dictates of style and taste require that women shall apply to all elements of dress an engaging and harmonizing scheme of colors. It is obvious that a single pair of shoes can ordinarily be worn in conjunction with but one color ensemble. It is the object of the present invention to provide a shoe comprising the usual structural elements with a strap or stay so arranged on the shoe that it can be disposed to exhibit any one of a plurality of surfaces of the strap. While it is known to provide removable straps or saddles, it has been found that the removable elements are easily lost. Furthermore, since women could purchase any number of removable elements for a single pair of shoes, the sales of the manufacturers decreased. The present invention provides a single pair of shoes with ornamental straps or stays which are permanently affixed and cannot be detached from the shoe, but which may be reversed to expose any one of a plurality of different colored surfaces or style effects. It is apparent that it is advantageous to provide a strap, which because it cannot be detached, cannot be lost.

More specifically, this invention consists in attaching a saddle strap or similar element to the shoe by means of a swivelled connection, to allow the strap to be pivoted as well as to affix the strap permanently to the shoe. Thus the invention accomplishes the object of supplying a strap for a shoe, which may be reversed to exhibit surfaces of different colors without the necessity of removing the strap from the shoe.

To illustrate, this invention may be employed on a shoe with vamp and quarters of a neutral or subdued color such as brown or gray. There thus is provided a shoe which, with one surface of the strap exposed, can be worn with one type of color ensemble and, upon reversal of the strap or stay to expose the other surface, can be worn in conjunction with an entirely different color scheme. Thus the utility of a single pair of shoes is multiplied. With a pair of shoes of this type the woman is not limited to a single color scheme, but has a wider field from which to match or contrast the colors of her apparel. Furthermore,

there is a benefit to the manufacturer in that his sales will be increased by reason of the novelty and utility of the shoe and will not be in danger of being decreased because each pair of shoes admits of a limited variety of colors.

A further object of this invention is to provide a shoe which with one side of the strap exposed expresses a style effect quite different from that exhibited when the strap is reversed. For example, an afternoon shoe can be constructed having one side of the strap colored to match the vamp and quarters, giving the effect of a street shoe. When the strap is reversed to expose a bright color or silver or gold, the style effect is that of an evening shoe.

These and other features of my invention will be best understood and appreciated from the following description of preferred embodiments thereof selected for purposes of illustration and shown in the accompanying drawings in which:

Figure 1 is a perspective view of one form of shoe embodying the invention.

Figure 2 is a side elevation of the shoe shown in Figure 1.

Figure 3 is a plan view of the forward section of the shoe shown in Figures 1 and 2.

Figure 4 is a detailed side elevation of the completed swivelled connection.

Figure 5 is a view in perspective of the swivelled connection before completion.

Figure 6 is a side view of another form of shoe embodying the invention.

Figure 7 is a view in perspective of another form of shoe embodying the invention.

Figure 8 is a side elevation of another form of shoe embodying the invention.

Figure 9 is a cross section along line 9—9 of Figure 8.

Figure 10 is a view in perspective of an additional form of shoe embodying the invention.

Figures 11 and 12 are detailed views of the strap or stay lined to indicate the differing colors on the respective surfaces of the strap or stay.

The stirrups 15 and 16, are fastened by means of small loops to the upper at 11 and 12 (see Figs. 1, 2, and 3). The oppositely disposed stirrup shaped elements 19 and 20 are attached by stitching 21 and 22 to saddle straps or stays 23 and 24.

As shown in Figures 4 and 5 the swivelled connection 17 is formed of two stirrup shaped elements 15 and 19. A block 25 bearing a pin 26 is formed on said member 15. The pin 26 passes through a hole 27 in the stirrup 19 and is then headed as shown at 28. In Figure 4, the dotted lines show the swivel when it has been turned

approximately 90 degrees and illustrate how one element of the swivel can be rotated independently of the other. Thus while members 15 and 19 are connected, they can be turned separately.

5 The saddle straps 23 and 24 (Fig. 1) are passed across the instep or saddle 29 of the shoe 14 and are engaged by buckles 30 and 31 of conventional design. These buckles are stitched to the outside quarter 34 of the shoe, (Fig. 3). When it is desired to obtain a different style effect or expose straps of colors different from those first seen, it is only necessary to disengage straps 23 and 24 from the buckles 31 and 30, pivot straps 23 and 24 through angles of 180 degrees, and reinsert the straps 23 and 24 in the buckles 31 and 30.

15 As shown in Figure 6, the heel foxing 35 terminates near the top portion of the inside quarter 13 of the shoe at a point located over the center point of the shank 36. The end of the heel foxing 20 35 is passed through the stirrup 15 of the swivelled connection 17 and back upon itself where it is stitched as shown at 37 to form a loop containing the base of the stirrup 15. A Sabot 25 type saddle strap 38 is stitched as at 21 to the stirrup 19 of the swivelled connection 17. This Sabot strap 38 passes over the instep and engages a buckle on the outside quarter of the shoe (not shown). The operation of the strap 38 in this embodiment of the invention is precisely the same as that of straps 23 and 24 described in the preceding paragraph.

30 In the embodiment of the invention as shown in Figure 7, the invention is applied to a T-strap, or T-stay. The stirrup 15 is attached to the tip 39 by a loop 40 formed in the tip 39 by stitching 41. Similarly stitched loop 42 of the T-strap 43 contains the base of stirrup 19. At the upper end of the T-strap 43 are cut two slots 44 and 45 which allow the passage of a retaining strap 46. 40 One end of the retaining strap 46 is attached by stitching along the upper edge of the inside quarter 47 of the shoe 48. After passing through the slots 44 and 45 in T-strap 43, the retaining strap 46 is engaged by a buckle of conventional design 49. This buckle 49 is stitched to the upper edge of the outside quarter 50 of the shoe 48.

45 When it is desired to reverse the strap and expose the opposite surface, it is merely necessary to disengage the retaining strap 46 from the buckle 49, remove it from the T-strap 43 by passing it out through slots 44 and 45, turn the T-strap 43 through an angle of 180 degrees, reeve the retaining strap 46 through the slots 44 and 45 in the T-strap 43 and reengage it in the buckle 49.

50 According to the embodiment of the invention in Figure 8, a Sabot saddle strap 51 is attached by a stitched loop 52 to a stirrup 19 forming part of the swivelled connection 17. To the other stirrup 15 of the swivelled connection 17 a piece of elastic goring 53 is attached. The goring is doubled upon itself to form a loop. The goring 53 is inserted during the construction of the shoe between the lasting margin 54 of the upper 56 and the outsole 55. In the case of a turned shoe the goring would be maintained in position by the stitching attaching the outsole to the upper, and in a cemented shoe the cement holding the outsole to the upper would also hold the goring 53 in place. A precisely similar construction is employed at the outside quarter of the shoe where the other end of the Sabot strap 51 is likewise secured by a swivelled connection and elastic goring (not shown).

55 It will be apparent that while both ends of the Sabot strap 51 are permanently secured to the shoe, reversal of the Sabot strap 51 is easily accomplished, since there are swivelled connections at both ends. The pieces of goring permit the swivelled connections 17 to be snugly secured close to the juncture of the upper and the outsole, while at the same time the swivelled connections 17 can be pulled from contact with the shoe and easily operated. The chief function is 10 to replace the buckle and maintain the shoe in close contact with the foot of the wearer.

15 Figure 10 shows the invention used in connection with a saddle strap consisting of two lace-stays 57 and 58. Although only one side of the 20 shoe 60 is shown, it will be understood that the elements of the invention not shown are precisely similar to those appearing in Figure 10. The stirrup 15 of the swivelled connection 17 is attached to a stitched loop 59 of the foxing 61. The lace-stay 57 is attached to the oppositely disposed stirrup 19 of the swivelled connection 17 by a stitched loop 62. In the lace-stays 57 and 58 are eyelets 63 arranged in conventional manner. Through these eyelets 63 the lacing 64 is 25 run. The lacing 64 serves to adjust the shoe to the foot of the wearer. When it is desired to have the reverse surfaces of the face stays 57 and 58 exposed to view, the lacing 64 is removed from the eyelets 63, the lace stays 57 and 58 are pivoted through an angle of 180 degrees, and the lacing 64 is once more run through the eyelets 63.

30 It will be noted that in Figures 11 and 12, the strap or stay is shown lined for tan on one side and for green on the other. It will be understood that the invention is not limited to this combination of colors, but that Figures 11 and 12 merely illustrate one combination of colors on the strap or stay.

35 Many modifications and embodiments of this invention will appear to those skilled in the art of making shoes, in addition to those embodiments shown in the drawings. However, this invention is not confined to those embodiments shown, but includes all modifications and exemplifications 40 thereof.

I claim:

1. The combination of a shoe and a strap having a plurality of surfaces of various aspects and a swivelled connection connecting one end of said strap to said shoe, said strap and connection being so constructed and arranged that said strap may be pivoted to expose a selected surface, thereby providing a plurality of different style effects.

2. The combination of a shoe and a strap having a plurality of different colored surfaces and a swivelled connection resiliently attached to said shoe, said connection securing said strap to said shoe, said strap and connection being so constructed and arranged that said strap may be 55 pivoted to expose a selected surface, thereby providing a plurality of different colored style effects.

3. As an element of a shoe, a strap having a plurality of surfaces of various aspects, said strap being pivotally secured to a shoe by a swivelled connection, whereby said strap may be pivoted to expose a selected surface, thereby providing a plurality of different style effects.

4. As an element of a shoe, a stay having a plurality of surfaces of various aspects, said stay being pivotally and resiliently secured to said shoe by a swivelled connection and elastic goring, whereby said stay may be pivoted to expose a selected surface, thereby providing a plurality of different style effects.

5. The combination of a shoe and a strap having a plurality of surfaces of various aspects and swivelled connections pivotally securing both ends of said strap to said shoe, and means for resiliently securing one of said swivelled connections to said shoe, whereby said strap may be pivoted to expose a selected surface, thereby providing a plurality of different style effects.
- 10 6. The combination of a shoe and a plurality of straps having surfaces of different aspects and swivelled connections securing one end of each of said straps to the shoe, said straps and connections so constructed and arranged that said straps may be pivoted to expose selected surfaces, thereby providing a plurality of different style effects.
- 15 7. The combination of a shoe and a plurality of
- lace-stays having a plurality of surfaces of various aspects and swivelled connections securing one end of each of said lace-stays to said shoe, said lace-stays and connections being so constructed and arranged that said lace-stays may be pivoted to expose selected surfaces, thereby providing a plurality of different style effects.
8. The combination of a shoe and a T-strap having a plurality of surfaces of various aspects and a swivelled connection securing the lower end 10 of said T-strap to said shoe, said T-strap and connection being so constructed and arranged that said T-strap may be pivoted to expose a selected surface, thereby providing a plurality of different style effects.

15
BENJAMIN BENJAMIN.
